US0D1058370S

(12) United States Design Patent (10) Patent No.: US D1,058,370 S
(45) Date of Patent: * Jan. 21, 2025

(54) BEVERAGE CONTAINER

(71) Applicant: BUZZBALLZ, LLC, Carrollton, TX (US)

(72) Inventor: Merrilee Kick, Plano, TX (US)

(73) Assignee: BUZZBALLZ, LLC, Carrollton, TX (US)

() Term: 15 Years

(21) Appl. No.: 29/950,209

(22) Filed: Jul. 1, 2024

Related U.S. Application Data

(63) Continuation of application No. 29/930,383, filed on Feb. 29, 2024, now Pat. No. Des. 1,034,196, which is a continuation of application No. 18/506,811, filed on Nov. 10, 2023, now Pat. No. 11,932,441, which is a continuation of application No. 29/824,813, filed on Jan. 27, 2022, now abandoned, which is a continuation of application No. 16/800,195, filed on Feb. 25, 2020, now Pat. No. 11,338,955, which is a continuation of application No. 12/762,934, filed on Apr. 19, 2010, now Pat. No. 10,604,296.

(57) CLAIM

The ornamental design for a beverage container as shown and described.

DESCRIPTION

FIG. 1 is a side view of a beverage container showing my new design; and,

FIG. 2 is a bottom view thereof.

The broken lines in FIGS. 1 and 2 show portions of the beverage container that form no part of the claimed design. All other orthogonal views, and all perspective views, of the beverage container are not shown and form no part of the claimed design. Any surface, or any portion of any surface, of the beverage container not shown in FIGS. 1 and 2 forms no part of the claimed design.

1 Claim, 2 Drawing Sheets
